UNITED STATES PATENT OFFICE.

ALBERT G. HEINLE, OF ESPLEN, PENNSYLVANIA.

DESIGN FOR A RAILWAY-RAIL.

SPECIFICATION forming part of Design No. 27,217, dated June 15, 1897.

Application filed March 11, 1897. Serial No. 627,060. Term of patent 14 years.

To all whom it may concern:

Be it known that I, ALBERT G. HEINLE, a citizen of the United States of America, residing at Esplen borough, in the county of Allegheny and State of Pennsylvania, have invented a certain new and original Design in Rails, of which the following is a specification, reference being had therein to the accompanying drawings.

10 This invention relates to a certain new and original design for railroad-rails, of which the following is a specification, reference being had to the accompanying drawings.

15 Figure 1 is a side elevation showing my design. Fig. 2 is a vertical view.

As shown in the drawings, the leading features of my design consist of the head 1, of the rail 2, the lower portion of the head 3, the body portion connecting the head and foot 20 4, having flanges 5 5.

1 is the head of the rail; 2, the lower portion of the head.

3 is the body portion, connecting the head and foot 4, having flanges 5 5.

It will be seen that the lower portion 2 of 25 the head and upper portion 4 of the foot, having substantially the same contour, materially add to the strength of the rail.

What I claim is—

The design for a rail, as herein shown and 30 described.

In testimony whereof I affix my signature in presence of two witnesses.

ALBERT G. HEINLE.
